ACID CHLORIDE-FLUORIDE BATH FOR
NICKEL PLATING

Arthur H. Du Rose, Euclid, Ohio, assignor to The
Harshaw Chemical Company, Elyria, Ohio, a
corporation of Ohio

No Drawing. Application March 12, 1945,
Serial No. 582,423

3 Claims. (Cl. 204—49)

1
This invention relates to electrodeposition of nickel from "high chloride" solutions, and more particularly a chloride-fluoride bath omitting boric acid.

I have now discovered that the use of certain fluorides in nickel plating solutions of the high chloride type instead of the usual boric acid buffer is advantageous in respect to ductility of the resulting deposit, throwing power and freedom from pitting. The solution also remains clear at pH values above 5.0 whereas the usual bath buffered with boric acid becomes turbid. There is also a slight increase in brightness in the all chloride solution and solutions in which the nickel in solution is more than half derived from chloride.

By "high chloride" solutions I mean those in which at least 33 1/3 % of the nickel is from chloride, the remainder from sulfate.

As is well known, all-chloride nickel plating solutions normally yield more highly stressed deposits than do solutions high in sulfate. With the advent of equipment suitable for containing the all-chloride solution there has been substantial tendency in the last few years for workers in the art of nickel plating to experiment with solutions of the all-chloride or high-chloride type in an attempt to produce deposits no more highly stressed than those taken from the usual high-sulfate solutions. Surprisingly, the use of fluorides as described below results in marked reduction in stress in the deposit. For example, a half chloride bath using fluorides gives a deposit which is no more highly stressed than those derived from the normal high-sulfate bath. This comparison is between solutions buffered with fluoride on the one hand and with boric acid on the other, 15 to 30 grams per liter of NH₄HF₂ or equivalent fluorine content of other fluorides as described below compared with 37.5 grams per liter of boric acid in standard Watts bath, these being optimum concentrations in both cases. Still more surprisingly, the use of fluorides as described below gives improved results in respect to throwing power, pitting, brightness and buffering action.

Fluorides suitable for my purpose are HF, NaF, KHF₂, NH₄HF₂, NiF₂, and NiHF. These are used in quantity between 15 and 30 grams per liter in the case of NH₄HF₂ and in the other cases the

equivalent in fluorine content of 15 to 30 grams per liter of NH₄HF₂.

Suitable bath compositions are as follows:

5 Nickel chloride hexahydrate 33 1/3 % to 100%—grams per liter... 200 to
Nickel sulfate hexahydrate 66 2/3 % to 0%—do— 400
A substance of the class consisting of NH₄HF₂, HF, NaF, KHF₂, NiF₂, and NiHF and mixtures of a plurality thereof, the total fluorine content thereof being equivalent to NH₄HF₂—grams per liter... 15 to 30
Water—do—Remainder
pH (may be adjusted with HCl)— 2.5 to 5.5

10 10 Specific examples of preferred bath proportions according to the invention are as follows:

Example I

15	NiCl ₂ .6H ₂ O	grams	250
15	NH ₄ HF ₂	do	20
	Water to make	ml	1000

Example II

20	NiCl ₂ .6H ₂ O	grams	150
20	NiSO ₄ .6H ₂ O	do	150
	NH ₄ HF ₂	do	15
	Water to make	ml	1000

Example III

25	NiCl ₂ .6H ₂ O	grams	250
	NaF	do	12
	Water to make	ml	1000

Example IV

30	NiCl ₂ .6H ₂ O	grams	150
	NiSO ₄ .6H ₂ O	do	150
	NaF	do	20
	Water to make	ml	1000

Having thus described my invention, what I claim is:

1. A nickel plating solution essentially consisting of water from 200 to 400 grams per liter of a source of nickel of the class consisting of (1) nickel chloride and (2) nickel chloride plus nickel sulfate, in proportion such that at least 33 1/3 % of the nickel is from the chloride, HCl sufficient to produce a pH of from 2.5 to 5, and a source of fluorine of the class consisting of NH₄HF₂, HF, NaF, KHF₂, NiF₂, NiHF and mixtures of a plurality thereof, the total fluorine content of said source of fluorine being equivalent to from 15 to 30 grams per liter of NH₄HF₂.

2. A nickel plating solution essentially consisting of water, nickel chloride, HCl sufficient to produce a pH of from 2.5 to 5, and from 15 to 30

grams per liter of a substance of the class consisting of NH_4HF_2 , HF, NaF, KHF_2 , NiF_2 , NiHF and mixtures of a plurality thereof.

3. A nickel plating solution essentially consisting of water, from 200 to 400 grams per liter of a source of nickel of the class consisting of (1) nickel chloride and (2) nickel chloride plus nickel sulfate in proportion that at least 50% of the nickel is from the chloride, HCl in quantity sufficient to produce a pH of 2.5 to 5, and a source of fluorine of the class consisting of NH_4HF_2 , HF, NaF, KHF_2 , NiF_2 , NiHF and mixtures of a plurality thereof, the total fluorine content of said source of fluorine being equivalent to from 15 to 30 grams per liter of NH_4HF_2 .
